UNITED STATES PATENT OFFICE.

LAURENCE J. ROSAR, OF SCRANTON, PENNSYLVANIA.

CONTAINER FOR CIGARETTES AND MATCHES.

Application filed November 10, 1924. Serial No. 748,961.

To all whom it may concern:

Be it known that I, LAURENCE J. ROSAR, a citizen of the United States, residing at Scranton, in the county of Lackawanna and 5 State of Pennsylvania, have invented certain new and useful Improvements in Containers for Cigarettes and Matches, of which the following is a specification.

The present invention relates to containers for cigarettes and matches so constructed that the cigarettes will be carried in a large compartment and the matches in a small compartment of the container.

The container is built in two parts, 10 namely, an outer casing and an inner box 15 slidable in the casing. The container can be made from thin cardboard or the like, or thin sheet metal. In both cases, the box and casing are each made from a single 20 blank.

In the accompanying drawings, one embodiment of the invention has been illustrated, and—

Figure 1 shows a perspective view of the 25 container open and filled with cigarettes and matches;

Figure 2 is a longitudinal section of the container in closed position;

Figure 3 is a transverse section along 30 line 3—3 of Fig. 2;

Figure 4 shows a blank for the inner box;

Figure 5 is a blank for the casing, and

Figure 6 is an assembled perspective view of a slightly modified form of container.

35 In the drawings, reference numeral 10 represents an inner box and reference numeral 11 of the casing. Referring to Fig. 4 of the drawings this shows a blank of cardboard or similar material cut or stamped before folding. The dotted lines in said 40 Fig. 4 indicate the lines along which the blank from which the box is formed is to be folded and reference numeral 12 represents the top wall for the match compartment, 13 is the narrow end or bottom of this compartment, 14 the back wall thereof, and 15 and 16 the sides of the match compartment. These parts are all folded upwardly 45 along the respective dotted lines so that the top wall 12 will be spaced a distance equal to the height of the end 13 and the sides 15 and 16 from the back wall 14 when folded and the side edges of the top wall 12 will coincide with the free edges of the sides 50 15 and 16, but need not necessarily be joined thereto.

The back wall 14 is folded downwardly along a dotted line 17 against the top wall 18 of the cigarette compartment, which is then folded forward along the 60 dotted line 19 and the end portion 20 of the cigarette compartment is thereupon folded along the dotted line 21 when the top wall 18 will be spaced a distance substantially equal to the width of the end 65 portion 20 from the bottom wall 22 of the cigarette chamber, the side walls 23 and 24 being of the same width and folded along the dotted lines 25 and 26. Finally the flap 27 is formed by folding the blank along 70 line 28 and again along line 29 so that the flap portion 27 will form the end closure of the box while the portion 30 of the flap will extend in the direction of the fold formed along line 17 between the walls 14 75 and 18. It should be noted here, that all the folding takes place upwardly from the face of the blank as viewed in Fig. 4 with the exception of the fold along line 17 and that the said fold will be placed a short distance below the flap, folded along line 28, because the walls 14 and 18 are both of the same length and shorter than the bottom wall 22. The top wall 12 of the match compartment being still shorter will not reach 80 up to the said fold along line 17, so that the ends of the matches 32 contained in the match compartment will be exposed between the edge 31 of the top wall 12 and the fold along line 17. Similarly the said fold being 85 placed back of the open end of the box will expose the ends of the cigarettes 33 above the fold line 17, as shown in Fig. 1.

In Fig. 5 is shown a blank from which the casing is made. In this Fig. 5, reference numeral 35 indicates one inner side wall of the cigarette compartment in the casing and this wall is folded along the dotted line 36 upwardly against the partition 37 which is shorter than the side walls 35 and 39 and corresponds substantially in length to the walls 14 and 18 in Fig. 4 and is adapted to engage between the same when the box is inserted in the casing so that the recessed edge 38 abuts against the inner side of the fold along line 17, in Fig. 4, when the box is pushed into the casing. The opposite inner side wall 39 of the cigarette compartment is of the same length as the inner side wall 35 and is folded along the 100 dotted lines 40 and 41. The bottom of the casing is formed by a rectangular portion 105 110

42 against which the outer side wall 43 is folded along the dotted line 44 and the top 45 of the casing is folded against the side 43 along the dotted lines 46 and finally the 5 side 47 is folded along the dotted line 48. It should be noted that all the folding takes place in the same direction or upwardly along the dotted lines from the face of the blank, as seen in Fig. 5. It should also be 10 noted that the height of the side wall 43 between the folding lines 44 and 46 is greater than the height of the inner side walls 35 and 39 so that the folding line 36 will correspond to the dotted line 49 when the blank 15 has been completely folded. In this manner a small compartment will be formed between the partition 37 and the top 45 on the one hand, and a large compartment between said partition and the bottom 42 on 20 the other hand.

The reverse faces of the side walls 35 and 39 are covered with paste in order to secure the same to the outer side walls 43 and 47 respectively. The outer face of the 25 side wall 43 is covered by the usual composition for striking matches, as indicated at 50 in Fig. 1.

In Figs. 1, 2, and 3, the box and casing are shown assembled and when the box is 30 partly drawn out of the casing as seen in Fig. 1, the ends of the matches 32 and the ends of the cigarettes will be exposed, the flap 27 being bent back slightly for removal of the cigarettes. In Fig. 2 showing the 35 box and casing in closed position, the flap 27 covers the left end of the casing while the free end 30 of the flap engages under the top 45 of the casing. The walls 14 and 18 of the box are here shown embracing the 40 partition 37 the inner end of which abuts against the fold 17 between said walls and it is evident that this partition will not permit further pushing of the box into the casing after the end 13 of the match compartment and the end 20 of the cigarette compartment become flush with the right-hand 45 end of the casing, as seen in Fig. 2.

It is evident that both the box and the 50 casing may be made of the same material or that one of them may be made of one material and the other of a different material. The box may for instance be made of cardboard or other similar fibrous material, while the casing is made of sheet 55 metal such as gold, silver, tin, brass or the like. In the latter case the container may be provided with a separate lid or cover, as indicated in Fig. 6 of the drawings, where a cover 51, also metal, fits over the entrance 60 end of the casing 11.

Naturally the parts that have been described as pasted together when the casing is made of cardboard, would have to be soldered or riveted together when the casing 65 is made of metal.

Having thus described the invention, what is claimed as new is:

1. A container of the class described comprising a casing and a box slidably engaging in the same, said casing having a transverse partition spaced from its top and bottom walls, and said box having corresponding inner walls adapted to engage with said partition to limit the travel of the box in the casing in one direction and to provide separate compartments in the box. 70

2. A container of the class described comprising a casing and a box slidably engaging in the same, said casing having a transverse partition spaced from its top and bottom walls, and said box having corresponding inner walls adapted to engage with said partition to limit the travel of the box in the casing in one direction and to provide separate compartments in the box; said box having side and end walls integral with said inner walls. 80

3. A container of the class described comprising a casing and a box slidably engaging in the same, said casing having a transverse partition spaced from its top and bottom walls, said box having corresponding inner walls adapted to engage with said partition to limit the travel of the box in the casing in one direction and to provide separate compartments in the box; side and end walls for said box integral with said inner walls, said inner walls being shorter than the bottom of the box, and a flap hinged on said bottom adapted to fold in and engage with the adjacent edge of said inner walls. 90

4. A container of the class described comprising a casing having side walls and top and bottom walls, a partition extending longitudinally in the casing between the side walls thereof and dividing the casing into upper and lower compartments, a main receptacle sliding into said casing between 105 said partition and the bottom of the casing, and an auxiliary receptacle attached at one end to said main receptacle and sliding into said casing between the partition and the top wall of the casing. 110

5. A container of the class described comprising a casing having side walls and top and bottom walls, a partition extending longitudinally in the casing between the side walls thereof and dividing the casing into upper and lower compartments, said partition terminating in spaced relation to one end of the casing, a main receptacle 120 slid able into and out of the lower compartment of the casing through the last-mentioned end of the casing, and an auxiliary receptacle slid able into and out of the upper compartment of the casing, said receptacles having adjacent walls disposed upon opposite sides of said partition when 125 130

the receptacles are disposed within the casing and joined together in straddling relation to the partition for abutting engagement with the foreshortened end of the 5 partition to limit movement of the receptacles into the casing.

6. A container of the class described comprising a casing having side walls and top and bottom walls, a partition extending longitudinally in the casing between the side 10

walls thereof and dividing the casing into upper and lower compartments, a main receptacle slidably fitting within the lower compartment, and an auxiliary receptacle slidably fitting within said upper compartment and connected with the main receptacle and moving into and out of the casing with the main receptacle. 15

In testimony whereof I affix my signature.

LAURENCE J. ROSAR. [L. s.]
